AUTOMATIC AIR CONTROL MEANS

Bernard Morse Guthrie, Chicago, Ill., assignor to
Fairbanks, Morse & Co., Chicago, Ill., a cor-
poration of Illinois

Application November 8, 1935, Serial No. 48,839

18 Claims. (CL 137—152)

This invention relates to automatic air control means, and more particularly to improvements in an automatic air control device adapted for a variety of uses, and which may be employed to particular advantage in connection with domestic 5 stoker apparatus and the like.

For convenience in disclosing the invention, it is preferred to illustrate and describe a few selected embodiments thereof as applied to a 10 domestic stoker assembly which may be of conventional form. It is to be understood, of course, that the particular application in no way limits the use of the improved automatic air control to stokers, as the control is adaptable to a variety 15 of applications in other than stoker assemblies.

In the drawings, Fig. 1 is a diagram showing a number of pressure-volume curves illustrating certain stoker air supply characteristics, as obtained experimentally from tests made upon a 20 stoker assembly having a constant speed blower supplying a forced draft of air to the tuyères and retort of a domestic heating plant; Fig. 2 is a diagram of a plurality of pressure-volume curves obtained experimentally in the same manner as 25 were those of Fig. 1, but with the air supply under the control of an automatic air volume control mechanism embodying the improvements of the present invention; Fig. 3 illustrates an application of the control device of the invention to the 30 air supply apparatus of a conventional domestic heating plant; Fig. 4 is an enlarged side elevation of a portion of an air supply conduit showing the air control mechanism mounted thereupon; Fig. 35 is a transverse section of the conduit presenting an end view of the assembled air control, as viewed from line 5—5 in Fig. 4; Fig. 6 is a trans- 35 verse section of a portion of the control device as viewed from line 6—6 in Fig. 4; Figs. 7 and 8 are side and end elevations respectively, of a modified portion of the control device, the elevation of Fig. 8 being taken along line 8—8 in Fig. 7; Fig. 9 illustrates a modified form of automatic air 40 control device; Fig. 10 is a side elevation thereof, shown partly in section, as viewed from line 45 10—10 in Fig. 9; Fig. 11 is a transverse section of a portion of the modified device, as viewed from line 11—11 in Fig. 10; Fig. 12 is a transverse section of another portion thereof, as viewed from line 12—12 in Fig. 10; Fig. 13 illustrates, in 50 assembly elevation, a further modified form of control device embodying the features of the present invention; Fig. 14 is a transverse section of the modified device of Fig. 13, as viewed from line 14—14 of that figure; Fig. 15 is a fragmentary transverse section of the device, as viewed 55

from line 15—15 in Fig. 13; Fig. 16 is a transverse section of a portion of the control mechanism, as taken along lines 16—16 in Fig. 13, and Fig. 17 is a sectional detail elevation of a part of the device, as viewed from line 17—17 in Fig. 16. 5

Fig. 3 illustrates a stoker assembly, designated generally at 10, applied to a conventional domestic type of heating plant 11. The stoker assembly includes a fuel receiving hopper 12, a fuel conveyor 14 and conduit 15 enclosing the portion 10 of the conveyor extending between the hopper and the heating unit, an air blower shown in dotted lines at 16, an air delivery conduit 18 extending from the blower to the wind box 19 of the heater unit 11, and operating means (not 15 shown) for the stoker conveyor and blower. The heater unit includes a retort 20 provided with air tuyères 22. The stoker and heater organization described thus far may be of a type well known and widely used, but there are several disadvantageous features of such an installation, particularly with respect to the heater air supply, which, heretofore, have caused considerable trouble in attaining uniform and efficient combustion conditions in the heater. 25

Assume for purposes of illustration, that in the assembly above described, the stoker conveyor delivers fuel to the heater retort 20 at the rate of .6 pound per minute, and that the heat content of the fuel delivered averages 14,500 B. t. u. 30 per second. Under normal heater conditions, the volume of air required for effecting an efficient burning of this fuel would be approximately 128 cubic feet per minute. With a typical fuel bed substantially 8 inches in depth, it has been 35 found by test that a static pressure equivalent to approximately 1 inch of water, is required to force 128 cu. ft. of air per minute through the fuel bed. Assume now the stoker to be operating under the above stated conditions, with the blower 40 operating at a constant speed to deliver air at the required pressure, and that after a period of such operation, the thermostatic or other device controlling the operation of the stoker and blower in accordance with the heat requirements of the 45 space to be heated by the heater unit, causes a cessation in the operation of the stoker and blower. The fuel in the furnace retort continues to burn at a slow rate of combustion, and fresh fuel is not delivered to the retort until the stoker 50 operation is again initiated by the thermostatic or other control acting in response to a call for heat. During the period of inoperation of the stoker and blower, at least a portion of the fuel bed will be consumed, and as the fuel burns, the 55

fuel bed becomes more porous so that it will offer less resistance to the flow of air therethrough when the blower again supplies air to the tuyères and retort. Since the blower operates at a constant speed, and since less resistance will be offered by the fuel bed to the passage of air therethrough, an excessive volume of air will now pass through the fuel bed. Under such conditions, the fuel bed will be disturbed and fly ash will be scattered and deposited over the heating surfaces of the furnace. Should the scattering of fly ash be excessive, the finer particles of ash may be forced out of the furnace into various parts of the house or space to be heated, thus creating a dust nuisance. Moreover, since fly ash is an effective heat insulator, the ash deposited over the heating surfaces of the furnace will form an insulating blanket which will result in greatly reducing the furnace efficiency. Again, the excessive volume of air passing through the fuel bed will substantially prevent the building up of the fuel bed to the desirable depth of 8 inches, as above described, when the stoker again delivers fresh fuel to the retort. This last effect is the result of a greatly increased rate of combustion as caused by an excessive volume of air traversing the fuel bed, so that fresh fuel fed to the furnace retort is consumed as rapidly as it is delivered thereto. Heating of the excess air in the furnace also tends to reduce the efficiency of furnace operation.

It is readily apparent from the above illustration that to overcome the noted disadvantageous features of stoker and furnace operation, some means for controlling the volume of air supplied to the fuel bed, under varying conditions of the fuel bed, must necessarily be employed. An air-throttle or damper of ordinary type which may be set to limit the amount of air delivered to the furnace to any desired degree, would give, under certain conditions of furnace operation, a fair degree of combustion air control. But even with an ordinary damper in the air conduit, the volume of air delivered under varying conditions of the fuel bed, would not be regulated to effect the most desirable combustion conditions in the furnace.

Fig. 1 illustrates graphically the variation in volume of air delivered to the furnace fuel bed under varying pressure conditions of the bed, the several curves being obtained under different degrees of control of the air supply. It will be noted that the static pressure is given in inches of water and plotted as ordinates, while the volume of air is measured in cubic feet per minute and plotted as abscissae.

Curve AC illustrates the result obtained with a constant speed blower supplying air to the furnace without an air feed control of any kind.

60 The curve AC is obtained by establishing the point A independently of the stoker or any controlling means, the zero volume of air flow corresponding thereto, indicating a substantially closed duct or air system into which the blower dis-
65 charges. Obviously, as resistance to the air flow is decreased, due for example to decrease in fuel bed thickness or resistance, the volume of air delivered by the constant speed blower will increase, as indicated by this curve. The ordinate
70 FB, representing a pressure of 1 inch of water, which is the normal pressure required for a fuel bed of 8 inch depth under the furnace and fuel feed conditions hereinabove described, is produced to intersect the curve AC at B. The abscissa BN at this point of intersection, indi-

cates a volume of air of approximately 288 cubic feet per minute. As before noted, the normal volume of air required for efficient combustion is approximately 128 cubic feet per minute, so that with an uncontrolled air feed, the actual volume of air delivered to the furnace is more than twice the volume required. The ordinate YDL representing the volume of air required for an efficient combustion of the fuel, being 128 cubic feet per minute, intersects the curve AC at point Y, 10 and the ordinate FB at point D. The point Y indicates an excessive pressure while obtaining the desirable volume of air, whereas the point D represents the correct balance of pressure against volume of air supplied. Hence it is that in order 15 to obtain best combustion conditions in the furnace and fuel bed, a control of the volume of air supplied to the fuel bed must be maintained, so that a curve representing variations in pressure and volume of air feed will pass through point 20 D. The curve AP represents variations in pressure and volume as obtained with an ordinary type of damper in control of the air supply. The damper in this instance, must be set so that when 25 the fuel bed is approximately 8 inches in depth and offers a resistance to the flow of air therethrough of approximately 1 inch of water, the proper volume of air for efficient combustion will permeate the fuel bed. For fuel having a heat content of 14,500 B. t. u., the proper volume of 30 air and rate of air flow has been found to be approximately 128 cubic feet per minute, so that with the damper set properly, the curve AP may be made to pass through point D.

However, a damper having a fixed setting is not satisfactory for all conditions of the furnace fuel bed, as will be observed from an inspection of the curve ADP. For example, as the pressure decreases, say as a result of the partial consumption of the fuel bed, the velocity of air fed to the furnace will materially increase, giving rise to the objectionable conditions heretofore noted.

Hence it will be readily understood from the foregoing discussion, that some means, preferably automatic, for controlling the volume of air fed to the furnace in accordance with the rate of fuel feed and the varying conditions of the fuel bed, is most desirable and practically necessary for obtaining an efficient operation of the furnace. Such an automatic air throttling governor or air control is fully attained by the device embodying the present invention. In Fig. 3, the stoker housing is broken away as at 24, to reveal a preferred form of air control of the present invention, which may be designated generally as 25, applied to the air delivery conduit 18.

Again referring to the curves of Fig. 1, the curve ADE illustrates a characteristic of pressure-volume variation in the flow of combustion air which is greatly to be desired, for effecting an increase in the efficiency of furnace operation under varying operating conditions. The degree of air volume control indicated by the curve ADE may be obtained with the improved automatic control device 25 embodying the improvements of the present invention. It will be noted that, for a variation in static pressure of from approximately .8 to 1.6 inches of water, the volume of air delivered to the retort and tuyères remains substantially constant. It will also be observed that as the pressure approaches a minimum, indicating in many instances that the fuel bed is thin and about burned out, the volume of air delivered to the fuel bed actually diminishes, a

characteristic which is most desirable, as will be readily understood.

In the devices constructed according to the present invention, the structural elements of the regulators are so chosen and related that when adapted for the operation depicted by the curve AE of Fig. 1, there is no appreciable restriction of air flow until there is attained a rate of approximately 120 CFM. The pressure drop 5 from 2.3 to 1.6 inches is substantially inherent in and incidental to the characteristics of the blower utilized. Under normal conditions this portion 10 of the curve will not conform to actual stoker operation, the usual pressure ranges therefor 15 lying between .5 inch and 1.0 inch in the case of a stoker designed for air flow characteristics within the values indicated by Figs. 1 and 2.

As will be fully described hereinafter, the air control device of this invention is fully adjustable 20 for effecting a control of the air feed under a wide variation in fuel bed conditions, rate of fuel feed, grades of fuel used, capacity of the furnace and other variable factors of furnace operation. Fig. 2 illustrates a number of pressure-volume 25 curves obtained experimentally with different adjustments of the control device. Each of these curves has substantially the same form as that of the curve ADE shown in Fig. 1, and each has about the same characteristics of pressure-volume 30 variation. The curve No. 1 corresponds to the curve ADE of Fig. 1, and indicates the air volume control for a furnace operating under the conditions hereinabove described. Curve No. 2 indicates the degree of air volume control for a 35 furnace operating under different conditions than obtained for the curve No. 1, such for example, as a different rate of fuel feed, a fuel bed having a normal depth greater or less than 8 inches, or a different grade of fuel used. Curve No. 3 was 40 obtained under still different conditions of furnace operation.

As intimated hereinabove, the principal object of this invention is to provide a greatly improved automatic air control device which may have a 45 wide range of uses, but which is particularly applicable to domestic stoker and furnace assemblies for effecting an automatic and uniform control of the air feed to the furnace tuyères and fuel bed in accordance with changes in the combustion condition of the fuel bed.

Another object is to be found in the provision of a greatly improved air volume control device which is adapted to attain a regulation of the combustion air-flow in accordance with the characteristic indicated by the curve ADE illustrated 55 in Fig. 1. The device is fully automatic in its regulating function, and is capable of adjustment to provide for alterations in the grade of fuel fed to the furnace retort and the rate of fuel feed 60 thereto.

A further object is to be found in the provision of an automatic air control device for the purpose described, which will give a uniform and smooth regulation of air feed, this result being 65 attained through a novel arrangement of the elements of the assembly, so as to reduce or substantially eliminate any tendency for the control element to over-regulate through oscillation upon movement from one control position to another. 70 A still further object is to provide an improved control device for the purpose described, which is comprised of but a few elements each of which may be readily removed for repair or replacement, the assembled control being sturdy and easily adjustable 75 according to requirements therefor.

Yet another object is to provide, in an improved, automatic air volume control, means for readily effecting adjustments of the control mechanism to provide for changes in the rate of fuel feed and the grade of fuel used, the adjusting means including indicia of adjustment settings corresponding to the heat or combustion characteristics of the grade of fuel used, and the rate of fuel feed to the furnace. 5

Further objects and advantages may be found 10 from the following description and from the drawings.

Referring now to Figs. 4, 5 and 6 by suitable characters of reference, the air control device generally designated as 25 is mounted upon a portion 26 of the air feed conduit 18. The device comprises a frame member 28 which is carried by the conduit section 26 and may be secured thereto as by the screws 29. One end 30 of the frame is provided with a portion 32 extending 15 outwardly beyond the side wall 33 of the conduit 18, the extension supporting a depending arm 34 which may be formed integrally with the portion 32. A similar extension 36 and depending arm 37 extending beyond the conduit side wall 25 38, is provided on the opposite side of the end 30 of the frame. Each of the arms 34 and 37 carries an adjustable bearing element comprised of a pointed screw 40 threadedly engaging the supporting arm and provided with a lock nut 41. 30 The bearing screws rotatably support a shaft 42, the shaft extending freely through suitable openings 44 in the side walls 33 and 38 of the conduit section 26 and having its ends journalled on the points of the screws 40 in a well known manner. An air-reaction element or damper plate 45 is non-rotatably secured to the portion of the shaft within the conduit 26, and is held in assembly therewith as by the screws 46. 35

Extending outwardly beyond the wall 38 of the conduit 26 is a portion 48 of the frame 28, this portion being, by preference, disposed on the frame end 49 opposite the end 30. The frame portion 48 supports spaced, depending arms 50 and 52 which may be formed each as an integral part of the portion 48. The arm 50 carries a bearing element in the form of an additional screw 40, threadedly engaging the arm and provided with a lock nut 41. The arm 52 which is closely adjacent the conduit wall 38 as shown by Fig. 6, carries in fixed adjusted position, a pointed screw bearing element 54 which, by preference, threadedly engages the arm. The bearing elements 40 and 54 pivotally support one end of an arm 56 which carries on its opposite end a counter-balance or weight member 57. The weight 57 is shown in the drawings as being formed integrally with the arm 56, but it is to be understood that the weight may be a separate element adjustably secured to the arm 56 in any suitable manner. 50 55 60

The damper or air target 45 and weight 57 are preferably operatively connected in a manner now to be described. The shaft 42 pivotally supporting the damper element, carries a lever element 58, the lever being fixedly secured on one end to the end portion of the shaft 42 adjacent the frame arm 37. The connection between the shaft and lever may be made in any suitable manner, such that movements of the damper plate 45 will effect responsive movements of the lever. The free end 60 of the lever 58 is by preference, operatively connected to the arm 56 carrying the weight 57, through an extensible structure such as the turnbuckle assembly 61. 70 75

The assembly 61 comprises oppositely threaded screws 62 and 64 threadedly engaging the end portions of a connecting link 65. The screw 62 is provided on its free end with an eye-portion 66 which is pivotally secured to the end 69 of the lever 58, as by a screw 68. The screw 64 similarly provided with an eye-portion 69, has this eye pivotally secured, as by a screw 70, to a portion 71 of the pivoted arm 56 intermediate the ends of the arm. Manually rotating the link 65 will effect an extension or retraction of the screw arms 62 and 64 in a manner which is well known. Through the adjustable link 65, the angular position of the damper plate relative to the weight may be regulated at will, to provide for varying conditions of fuel feed and furnace operation.

As a means for limiting movement of the damper in the direction to reduce the flow of air through the conduit, a lug or stop element 67 is by preference formed on the bearing arm 37, the stop extending inwardly of the arm and in the path of movement of the lever arm 58 (Figs. 4 and 5). Thus, since the arm 58 is connected with the damper through the shaft 42, the arm 58 striking the stop 67 will effectively prevent further movement of the damper in the air flow cut-off direction.

The operation of the automatic air control is such that movements of the damper as effected by the air flow through the conduit 18, in the direction indicated by the arrow in Fig. 4, result in movements of the weight 51, the relatively large inertia of the weight, of course, tending to oppose any movement of the damper. The lever system between the damper and weight, comprised of the lever 58 and the adjustable lever 61, is arranged to effect a greater angular movement of the weight than that of the damper plate, the preferred ratio of movement being approximately two to one. This multiplied movement of the counterbalancing weight 51 serves to prevent overregulation of the air supply upon changes taking place in the condition of the fuel bed. For example, if the angular movement of the weight were equal to that of the damper plate, then in the event of a change in the volume of air flow through the conduit, the damper would be moved to counteract the increased volume of air and at the same time the weight would be moved. But because of its greater inertia, the angular swing of the weight will carry the damper beyond its position for proper regulation, and upon the return swing, the damper will be carried beyond the proper position in the opposite direction. Thus an oscillation tends to be set up, resulting in an erratic control of the volume of air flowing through the duct. By providing a lever system between the damper and weight so that angular movements of the weight will be approximately twice as great as the angular movements of the damper, the tendency for the control device to oscillate will be practically eliminated. The increase in the inertia of the weight when its angular acceleration is increased, results in a greater dampening effect thereof, hence the damper will not respond quickly to slight variations in the volume of air flow and thus is obviated an otherwise existing tendency to overregulate. It may be noted that a suitable dash pot or equivalent device (not shown by Fig. 4, but appearing in Fig. 13) may be employed in cooperation with the above described structure

to assist in the control of damper movement for preventing overregulation of the combustion air.

It is to be understood that in the above described embodiment of the air control device and in the modifications thereof illustrated in the drawings and presently to be described, the dimensions of the damper element or air target, the mass of the counterweight and the leverage ratio of the mechanism operatively connecting the weight and the damper element, are definitely predetermined for control devices of a given capacity, so that the cooperative relation of the elements results in a control device which will give a form of combustion air flow regulation having the desirable characteristics illustrated by the curve ADE in Fig. 1.

Figs. 7 and 8 illustrate a modification of portions of the control structure shown in Figs. 4 through 6. For convenience, those elements appearing in the modified structure which have not been changed or modified over the corresponding elements shown by the preceding figures, will be given the same reference characters. The modified structure now to be described, provides an adjustment feature in addition to that afforded by the turnbuckle assembly 61. The end of the damper carrying shaft 42 which is pivotally supported by the depending arm 31 of frame 28, supports a disc sector element 72, the element being secured at its axial end 74, to the shaft, as by a key connection 75, so that regulating movements of the air target or damper 45 will be transmitted to the element 72. The shaft 42 also supports a lever 76, the upper end 78 of which is freely pivoted to the shaft adjacent the end 74 of the element 72. The eye portion 66 of screw 62 is pivotally connected to the free end 79 of the lever 76, as by a screw 80. The lever 76 and sector element 72 must be operatively connected so that regulating movements of the damper plate 45 will be transmitted to the weight. This may be conveniently effected through a screw connection between the lever and disc element. The disc sector is by preference provided with a plurality of spaced, threaded holes 82 arranged along the peripheral portion of the sector in the manner illustrated in Fig. 7. The lever 76 carries intermediate its ends, a threaded bolt element 83 which passes freely through the lever and threadedly engages the sector, in any one of the holes 82, thereby effecting an operative connection between the lever and sector element. The connection may be made selectively, in any one of the tapped holes 82, whereby to effect a change in the angular position of the damper plate 45 with respect to the longitudinal axis of the lever 76, and which in turn will effect a change in the relative angular relation between the damper and the weight. Thus the angular relation between the weight and damper, in their normal positions of rest, may be initially or coarsely adjusted through the bolt connection between the lever 76 and sector element 72, and finally or more accurately adjusted by means of the turnbuckle assembly 61. Movement of the damper in the direction to reduce the volume of air flow through the conduit is limited by a stop element 81 provided on the bearing arm 37, the stop by preference being in the form of a finger or lug extending into the path of movement of the sector element 72.

It is to be understood, of course, that in the above described adjustable arm and sector arrangement for effecting initial or coarse adjustments of the damper element relative to the in-

ertia element, the spaced, tapped holes 82 may be replaced by a continuous slot or recess of arcuate form (not shown), while the bolt 83 may be replaced by a clamping device (not shown), having a part thereof extended through the slot. An ordinary bolt and nut type of clamp may well serve this purpose, and the manner of its application to the arm 16 and a slotted portion (not shown) of the sector 72 is thought to be quite obvious. It is contemplated that this preliminary, or relatively coarser adjustment may be made as necessary to care for differing air requirements in accordance with differing predetermined rates of fuel feed, such as provided, for example, by a speed change gear unit (not shown) serving to connect the conveyor 14 to the driving element such as an electric motor (not shown).

The modified control device as shown by Figs. 9 through 12, employs a geared connection between the damper shaft and the weight shaft, the gears taking the place of the lever connections or linkage between the damper and weight shafts of the control device shown in Fig. 4.

The supporting frame for the elements of the latter modified control is comprised of a plate member 84 which is secured to the section 26 of the air supply conduit 18, as by the screws 86, and a box-like housing 87 which is secured to the end portion 88 of the plate 84, preferably by welding as at 90. The opposite end 91 of plate 84 extends outwardly beyond the conduit side wall 33 and downwardly as at 94 to provide a support for a bearing element 95. The bearing 95 may be secured to the portion 94 in any suitable manner, preferably by welding as at 96. The outer side wall 98 of housing 87 supports an adjustable bearing element comprised of a pointed screw 99 threadedly engaging a nut 100 and passing freely through the wall 98. The nut is fixedly secured to the wall as by welding at 102. The bearing elements 95 and 99 pivotally support a shaft 103 which extends through suitable openings 104 in the side walls 38 and 33 of the conduit 26. A damper plate 107 is secured to the portion 110 of the shaft within the air conduit 26, preferably by the screws 108. The shaft 103 is by preference of square section over the greater portion of its length, as a matter of convenience in securing the damper plate thereto. The shaft end portion 110 adjacent the adjustable bearing 99 is preferably formed round and of reduced section, whereby to form the shoulder 111. The shaft end 110 carries a gear element 112 which is secured to the shaft against the shoulder 111 in any suitable manner, such as by pressing the gear over the shaft end.

The housing 87 is provided with an inner side wall 114 overlying a portion of the conduit wall 38, and a slot 115 is formed in the wall so that the wall may clear the shaft 103. Referring particularly to Figs. 10 and 11, the wall 114 supports a bearing element 116 which is fixedly secured to the wall preferably by welding, as at 118. The outer housing wall 98 carries an adjustable bearing comprised of a pointed screw element 119 threadedly engaging a nut 120 and passing freely through the wall. The nut 120 is secured to the wall as by welding at 122. The bearing elements 116 and 119 pivotally support a square shaft 123 having a rounded end portion 124 adjacent the bearing element 116. The juncture of the square and round portions of the shaft forms a shoulder 126 for limiting axial movement of a pinion 127 carried by the rounded portion of the shaft. The pinion may be operatively secured

to the shaft as by pressing it over the shaft end. In assembly, the pinion meshes with the gear 112, so as to be operated by the gear, in response to regulating movements of the damper plate 107. The squared portion of the shaft 123 has secured thereto a depending arm 128, the upper end of the arm being welded to the shaft, as at 130. The arm supports a weight element 131 which may be adjustably positioned along the arm, the weight being provided with a set screw 132 for securement to the arm in any adjusted position. The side wall 117 of the housing, being the wall adjacent the counterweight supporting shaft 128, is cut away on its lower portion as at 121, to permit the arm 128 to swing upwardly therethrough during regulating movement of the damper and weight mechanism. The marginal portion 125 of wall 117 defining the upper limit of the cut away portion 121, serves as a stop for the arm or shaft 128, whereby to limit the swinging movement of the arm and counterweight, and hence of the damper element 107, in a direction to reduce the flow of combustion air through the conduit.

The operation of the modified air control is similar to that of the first described air control device, the increased movement of the weight relative to the movement of the damper being obtained through the gear and pinion, which may be formed to give a two to one ratio of movement. It will be apparent that the initial relative angular position of the damper and weight may be altered or adjusted to any desired degree, simply by meshing the pinion with the gear in the assembly of the control structure, in such manner as to effect the desired angular relation.

Figs. 13 through 17 illustrate a further modified air control mechanism embodying the improvements of the present invention. The control mechanism is, by preference, carried by a frame 134 which may be mounted upon a portion of the air supply conduit 18, and secured thereto as by the assembly screws 135. The frame is provided, near one end thereof, with laterally projecting arms 136 and 138, the arm 136 extending beyond the side wall 38 of the conduit 18 and the arm 138 outwardly beyond the opposite conduit side wall 33. A bearing lug or member 142 is carried by the arm 138 adjacently to and extending substantially vertically below the free end of the arm. It is preferred to form the member 142 as an integral part of the arm, as shown in Fig. 14. The lug supports a bearing element in the form of a pointed screw 143 which threadedly engages the bearing lug with the screw point directed inwardly thereof, toward the conduit. The bearing screw may be adjusted in the supporting lug, toward or away from the conduit, and may be locked in its adjusted position as by a lock nut 144. The arm 136 is provided, in a similar manner, with a bearing lug 146, an adjustable bearing element 147 and bearing lock nut 148.

The bearing elements pivotally support a shaft 150 which extends laterally through the upper portion of the conduit 18, through suitable openings 151 in the side walls thereof. The shaft supports a damper plate 152 within the conduit, the plate being secured on one end thereof, to the shaft by suitable screws 154. The direction of air flow through the conduit is indicated by the arrow in Fig. 13, and the pivotal arrangement of the damper 152 with respect to the direction of air flow, is such that the flow of air will tend to actuate the damper toward damper- 75

closed position, whereby to reduce the volume of air flow.

The portion of the shaft 150 located externally of the conduit 18 and extending between the conduit wall 38 and the bearing element 147, carries a frame member 155 of substantially U-shape, the frame being freely pivoted at its upper end 156, to the shaft in the manner illustrated by Figs. 13 and 14. Axial movement of the frame toward the conduit wall is, by preference, limited by a shouldered portion 158 on the shaft 150. The frame 155 comprises spaced, parallel arms 159 and 160, each provided on its inner face with a longitudinally extending guide flange 162. The flanges are arranged in opposed relation as shown in Figs. 13 and 17, and support a member or block 163 for sliding movement longitudinally of the frame, the block having formed in opposite edges thereof grooves 164 for the reception of the guide flanges. The sliding movement of the block is controlled preferably by a screw 166 threadedly engaging a lug 167 carried by the block as an integral part thereof as shown in Figs. 16 and 17. The screw is supported upon the frame 155 in a pair of spaced, parallel bearing members 168 and 170, the members bridging the arms of the frame and formed, preferably, as an integral part thereof. The screw is provided, adjacent the screw head 171, with a shouldered portion 172 which in the assembly of the screw to the frame, abuts the bearing member 170 (Fig. 16). The opposite end portion 174 of the screw is journaled in the bearing member 168, and is provided with a retaining lock pin 175 and washer 176 in abutting relation with the outer face of the bearing member. Thus the screw may be rotated freely in the bearing members, and without axial displacement thereof, as such movement is prevented by the shouldered portion 172 and the lock pin 175. Rotation of the screw in either clockwise or counterclockwise direction will, of course, cause the block 163 to slide along the frame 155 either toward or away from the pivoted frame end 156. The outer face portion 178 of the block is provided with a plurality of substantially rectangular recesses or grooves 179 for a purpose which will presently appear. As shown in Fig. 13, the several recesses are by preference, angularly or radially spread, 50 fan-like, over the surface of the block.

The shaft 150 pivotally supporting the damper plate 152 and frame member 155, also carries an arm element 180 which has its upper end 182 engaging the shaft adjacent the end portion 156 of frame 155. The end portion 182 of arm 180 is secured to the shaft preferably through a key connection 183, so that pivotal movements of the damper plate 152 and shaft 150 will effect responsive pivotal movements of the arm 180. The free end 184 of this arm carries a spring-actuated projection or plunger element 186 (Fig. 17) which is adapted to engage and seat in any one of the slots 179 disposed in the face 178 of the block 163. The plunger assembly comprises a plunger-operating member or handle 187 threadedly secured to the plunger element 186, a spring retaining barrel 188 secured to the free arm end 184, and a compression spring 190 seated in the barrel and having one end 191 abutting a flanged portion 192 on the barrel, and its opposite end 194 seated against a flange element 195 carried by the plunger. The structural features and operation of the plunger-assembly 70 presently described and illustrated are well

known, and hence need not be described further herein.

It will be readily seen that the plunger in engagement with any one of the slots in the block element 163, forms an operative connection between the arm 180 and the pivoted frame 155, whereby air regulating movements of the damper plate will be transmitted to the frame 155. The rectangular slots in the block 163 permit the block to be adjusted along the frame 155, while the plunger operatively engages any one of the slots, the purpose for this adjustment feature appearing hereinafter.

The frame 155 is provided with an outstanding lug portion 196 on the arm 160, serving as a pivotal seat for one end 198 of a rod or link element 199, the opposite end 200 of rod 199 being pivotally connected to an arm 202 supporting an inertia element 203. The pivotal connection of the rod end 198 to the lug 196 is, by preference, made through a friction-reducing structure such as the ball bearing assembly 204, the outer race 206 thereof being carried by the lug 196, while the inner race 207 is secured to the rod end 198 as by the bolt 208 and securing nut 210. As shown in Fig. 14, the rod end 198 is furcated so as to embrace opposite sides of the lug 196, to facilitate connection thereof to the inner race element 207. The pivotal connection of the rod end 200 to the weight arm 202 is by preference, effected in a similar manner, through the friction-reducing assembly 211, the bolt 212 and securing nut 214. However, in this instance, the outer race of the assembly 211 is carried by the rod end 200, while the inner race is secured to the weight arm, as by the bolt 212 and nut 214 (Fig. 15).

The free end 215 of arm 202 carrying the inertia element 203, is pivotally connected to an outstanding bearing arm 216 carried by and forming a part of the frame 134. The bearing arm 216 is arranged on the end portion of the frame opposite, and is parallel to, the frame end 136 supporting the bearing arm 146. The pivotal connection of the arm 202 to the bearing arm 216 is by preference, effected through a friction-reducing journal assembly, with the outer race element 219 thereof seated in a portion of the bearing arm 216, and the inner race 220 secured to the end 215 of arm 202 as by the bolt 222 and clamping nut 223.

In the last described embodiment of the invention, the lever system connecting the counter-balancing weight 203 with the damper plate 152, comprised of the arm 180, frame 155, lever 199 and weight arm 202, is arranged to effect a greater angular movement of the weight than of the damper plate. This multiplied movement of the counterweight serves to prevent overregulation of the air supply in the manner hereinbefore described. As a further means for preventing overregulation of the air supply, it is preferred to apply an additional or secondary movement-retarding force to the lever system. This additional retarding force may be very effectively obtained through the application of a suitable dash-pot device to the lever system. A dash-pot of conventional form is shown at 225 in Fig. 13, wherein the cylinder 226 thereof is pivotally supported at one end upon a pin 227 carried by suitable bearing lugs 228 secured to the frame 134. The dash-pot piston rod 230 is pivotally connected on its free end 231 to an arm 232 extending laterally of and formed as a part of the lever 199. Thus displacement of the lever 199 resulting from regulating movement of the damper 152 will be retarded to a desirable degree by the dash-pot 225 operating 70 75 80 85 90 95 100

in conjunction with the counterbalancing weight 203.

As in the previously described embodiments of the invention, movement of the damper plate 152, in the direction to reduce or cut-off the flow of air through the conduit, is limited by a suitable stop device. In the present example, the stop device comprises a lug or abutment 234 carried by the frame 134, and a projection 235 formed on the 10 arm 180 and arranged to engage the lug as the arm swings to the left (Fig. 13). As the arm 180 is operatively connected to the damper 152, engagement of the projection 235 with the lug 234 will effectively prevent further movement of the 15 damper in a clockwise direction about its pivotal support 150.

The air control operation of the modified device presently described, is similar to that of the control devices earlier referred to, and hence such 20 operation need not be repeated. It will be observed from the arrangement of the several elements comprising the control device, that movements of the damper element 152, as effected by changes in the volume of air flow through the 25 conduit 18, will be transmitted to the inertia element 203, the inertia element of course, tending at all times to counteract such movements of the damper plate. As hereinabove intimated, the provision of the U-shaped frame 155, slidably 30 carrying block 163, and the several slots 179 arranged in the block for receiving the plunger element carried by the damper arm 180, serves to permit the adjustment of the control mechanism in accordance with predetermined operating conditions of the stoker and heater assembly to which the control device is applied. For example, the 35 thermal value of fuels vary, so that if a grade of fuel having a heat value of 14,000 B. t. u. per pound is delivered at a given rate to the furnace 40 retort, a certain volume of air per unit of time will be required for the efficient combustion of such fuel. Hence, the initial setting of the damper plate must be such as will permit the required volume of air to flow to the furnace retort and 45 tuyères. For a different grade of fuel having say a heat content of only 12,000 B. t. u. per pound, the initial setting of the damper plate must be adjusted so that the correct volume of air will be delivered for efficient combustion of this grade of fuel. The adjustment of the control device to 50 effect different initial settings of the damper plate, is made through the sliding block 163, which when actuated by the screw 166, will effect a change in the angular position of the damper 55 within the conduit 18. The effect of this adjustment is to change the initial relative angular relation of the inertia element and the damper plate.

To facilitate proper adjustment of the control device for the purpose above described, suitable 60 indicia of control settings, indicated at 224, are arranged in scale form, say along an inner marginal portion of the arm 160 of the U-shaped frame, (Fig. 13). The setting of the block 163 relative to the scale 224 is indicated by a suitable 65 notch or pointer 226 disposed on a marginal portion of the block opposite the scale. The scale 224 is by preference graduated in units of fuel heat content or B. t. u.'s per pound, and its calibration is effected in accordance with a predetermined relative position of the sliding block 163 and its supporting frame 155, corresponding to the 70 initial angular position of the damper element 152 required to admit the desired volume of air for the efficient combustion of the particular 75 grade of fuel burned.

As before described, the operative connection between the damper plate and the sliding block is effected through the damper arm 180 carrying the spring-pressed plunger 186 which is adapted to engage any one of the rectangular slots 179 in 5 the face of the sliding block. It will readily be seen that by changing the plunger connection from one slot to another, the angular setting of the damper plate relative to the inertia element, will be altered. For convenience in effecting adjustment of the control device for different rates of fuel feed, the several slots 179 are numbered 1, 2 and 3 from left to right, the numerals indicating optimum damper settings corresponding to different predetermined rates of fuel feed. Thus 10 when the plunger element 186 carried by the damper arm 180 is engaged in the slot designated by the numeral 1, the damper plate will be angularly set relative to the inertia element for regulating the air supply in accordance with a 15 predetermined rate of fuel feed. Engaging the plunger in slot 2 adjusts the damper to control the air supply in accordance with a second predetermined rate of fuel feed, and so on.

While only three slots are shown in the sliding block 163, it is to be understood that the number of slots may be increased where it is desired to effect adjustments of the air control for a greater number of different rates of fuel feed.

Adjustment of the control device then, to effect an automatic control of the air supply to the furnace tuyères in accordance with a predetermined rate of fuel feed and the grade of fuel used, may be readily and easily effected simply by seating the plunger 186 in the slot corresponding to the predetermined rate of fuel feed and adjusting the sliding block 163, through screw 166, so that the match mark 226 is disposed in alignment with the particular division of the scale 224 corresponding to the predetermined heat content 35 of the fuel delivered to the furnace. The effect of the above described adjustment is to vary the initial angular setting of the damper plate relative to the inertia element, so that in the operation of the heating plant, the control device will 40 automatically regulate the volume of air supplied to the fuel bed in accordance with changing conditions in combustion.

The operation of the device illustrated by Figs. 13 through 17 is thought to be apparent from the 50 description of operation of other embodiments of the invention, but may be briefly described as follows: Any appreciable increase in rate and volume of air flow in the direction of the arrow (Fig. 13) tends to move the damper element 152 in a direction to restrict the area of opening through this portion of the duct. Such movement of the damper element is opposed, through the connections described, by the inertia element 203, so that any substantial movement of the damper 60 takes place only by shifting the position of the inertia member. Once the several adjustments of the device of Fig. 13 have been effected in accordance with heat value of the fuel and predetermined rate of fuel feed, the linkage connecting 65 the damper 152 to the inertia element will operate substantially as if there were a rigid arm connecting the damper pivot to the end 198 of arm 199, whereby there is provided, with advantages noted, a motion-multiplying connection between 70 the damper and inertia element. It results from this that as the damper is displaced in a direction to restrict the flow of air, the inertia element is displaced from its normal position of rest to an even greater extent, so that the arrangement 75

disclosed serves efficiently to prevent hunting or overregulation. The parts are so selected and operatively related, as in certain of the preceding embodiments, as to result in pressure-volume characteristics substantially as shown by the curve ADE of Fig. 1.

The several embodiments of the invention described hereinabove and illustrated by the drawings, fully attain the foregoing objects, and in addition, each of the several constructions is sturdy and dependable for a fully automatic operation thereof, requiring little or no care once the mechanism is adjusted according to particular requirements of furnace operation.

15 It is to be understood, of course, that the presently described embodiments of the invention may be altered or modified without affecting the spirit and full intended scope of the invention, as defined by the appended claims.

20 I claim:

1. In a stoker assembly, an air supply conduit, an automatic air throttle including a target damper in said conduit, a swingably mounted weight, for yieldably opposing operation of said target damper, an adjustable connection between the damper and the weight adapted for increasing the effect of the weight during air throttling operation of the damper, and a dash pot also connected to the damper and tending to suppress movements thereof in response to changes in movement of air through the conduit.

2. In a stoker assembly, an air supply conduit, an automatic air throttle including a target damper in said conduit, a swingably mounted weight, a dash pot, a motion-amplifying connecting linkage between the target damper and the dash pot and weight, and means associated with said linkage for adjusting the relative normal positions of rest, of the damper and the weight.

3. A draft regulating device comprising in combination with an air conduit, a frame, a draft control member carried by the frame and arranged in said conduit for regulating air movement therein, in response to the flow of air through the conduit, an inertia member pivotally carried by the frame and tending to oppose regulating movement of said control member, and motion-amplifying means forming an operative connection between said members, said means including a plurality of elements, one thereof being adjustable for regulating the initial operative relation of said members relative to each other.

4. In combination with a stoker assembly including a retort, a source of air supply and a conduit for conveying air from said source to the retort, an air control element in said conduit, responsive for its control operation to the flow of air therethrough, angularly displaceable inertia means tending to oppose operation of said control element, and means forming an operative connection between said opposing means and control element, and adapted to increase the effect of said opposing means during control operation of said element, said last means being adjustable for regulating the initial operative relation of said opposing means and control element.

5. In combination with a stoker assembly including a retort, a source of air supply and a conduit for conducting air from said source to the retort, a frame, a draft regulating member carried by the frame and disposed for pivotal movement in said conduit, said member being responsive for its regulating movement to the flow of

air through the conduit, an inertia member pivotally carried by the frame and tending to oppose movement of said regulating member, and motion-amplifying means operatively connecting said members and adapted for increasing the effect of said inertia member during movement of said regulating member, said means including a plurality of elements, at least one thereof being adjustable for regulating the initial angular relation of said members relative to each other.

6. A draft regulating device comprising in combination with an air conduit, a draft control member in said conduit arranged for control actuation in response to the flow of air through the conduit, a swingable inertia member tending to oppose regulating movement of said control member, and motion-amplifying means operatively connecting said members, and including a lever and an extensible linkage structure pivotally connected to the lever and to the inertia member.

7. In combination with a stoker assembly including a retort, a source of air supply and a conduit for conducting air from said source to the retort, a frame, a draft control member carried by the frame and arranged for pivotal movement in said conduit, said member being responsive for its regulating movement, to the flow of air in said conduit, an inertia member pivotally carried by the frame and provided for opposing regulating movement of said control member, and means forming an operative connection between said members, said means including an element pivotally actuated in response to regulating movement of said control member and an extensible device pivotally connected to said element and to the inertia member.

8. In a stoker assembly including an air supply conduit, an automatic air throttling governor assembly including an air target rockably disposed in the air supply conduit, a damping device rockably mounted on an axis spaced from that of the target, a linkage for translating movement of the target to the damping device, adjustment means providing for a coarse or substantial variation of initial angular position of the target, and a distinct device adapted to permit a finish adjustment between the target and the damping device.

9. In an air throttling governor assembly for use in the air supply conduit of a coal stoker, an air reaction element in the conduit, an inertia element, said elements being rockably mounted for movement about spaced axes, a motion amplifying connection from the air reaction element to the inertia element, means providing a coarse adjustment of the initial angular setting of the air reaction element relative to the inertia element, and means providing a finer or finish adjustment of such angular relation.

10. A draft control device comprising in combination with an air conduit, a draft control member in said conduit, responsive for its control movement to the flow of air through the conduit, an inertia member tending to oppose control movement of said control member, and means including a pair of coacting rotary elements, forming an operative connection between said members, said means being adapted to increase the effect of said inertia member during control movement of said control member.

11. In combination with a stoker assembly including a retort, a source of air supply and a conduit for conducting air from said source to the retort, a draft regulating element in said conduit responsive for its control movement to

the flow of air through said conduit, a frame, an inertia element pivotally carried by the frame and tending to oppose movement of said regulating element, and means forming an operative connection of gear type between said elements and arranged for increasing the effect of said inertia element during control movement of said regulating element.

12. In combination with a stoker assembly including a retort, a source of air supply and a conduit for conducting air from said source to the retort, a draft regulating element in said conduit, responsive for its control movement to the flow of air through said conduit, a frame, an inertia element pivotally carried by the frame and tending to oppose movement of said regulating element, and adjustable means forming an operative connection between said elements and arranged for increasing the effect of said inertia element during control movement of said regulating element, said means including rotatable elements carried by the frame, said elements being detachably connected in selected relations for effecting adjustment of said connecting means.

13. A draft control device comprising in combination with an air conduit, a draft regulating member in said conduit, responsive for its control movement to the flow of air through the conduit, an inertia member tending to oppose control movement of said regulating member, and means forming an operative connection between said members, said means including an element actuated in response to movements of said regulating member, a lever mechanism and an adjustable device connecting said element to said lever mechanism.

14. A draft control device comprising in combination with an air conduit, a draft regulating element disposed in said conduit and responsive for its control movement to the flow of air therethrough, an inertia element tending to oppose control movement of said regulating element, a member actuated in response to movements of said regulating element, a member operatively connected to said inertia element, and an adjustment device serving to complete an operative connection between said members, said device including a projection and means recessed to provide a plurality of seats for said projection.

15. In combination with a stoker assembly including a retort, a source of air supply and a conduit for conducting air from said source to the retort, a draft regulating element disposed in said conduit and responsive for its control movement to the flow of air therethrough, an inertia element tending to oppose control movement of said regulating element, a member actuated in response to movement of said regulating element, and adjustable means connecting said member to said inertia element and forming with said member an operative connection between said elements, said means including a guide member, an element slidably adjustable in said guide member and having grooves therein, and a retractable plunger operatively engaging a groove in said slidable element.

16. In combination with a stoker assembly including a retort, a source of air supply and a conduit for conducting air from said source to the retort, a draft regulating element disposed in said conduit and responsive for its control movement to the flow of air therethrough, a frame, an inertia element tending to oppose control movement of said regulating element, pivotally carried by said frame, a member also carried by said frame and arranged for pivotal movement in response to control movement of said regulating element, and means associated with said member and forming an operative connection between said elements, adapted for increasing the effect of said inertia element during control movement of said regulating element, said means including a guide member pivotally carried by the frame, an element adjustably carried by said guide member and detachable means operatively connecting said adjustable element to said member.

17. In combination with a stoker assembly including a retort, a source of air supply and a conduit for conducting air from said source to the retort, a frame, a draft regulating member carried by the frame and arranged for control movement in said conduit in response to the flow of air through the conduit, an inertia member pivotally carried by the frame and tending to oppose control movement of said regulating element, an arm also carried by the frame and movable responsively to control movement of said regulating member, means associated with said arm and forming therewith an operative connection between said members, said means comprising a guide member pivoted to the frame, a lever connecting the guide member to said inertia member, an adjustment device slidably carried by said guide member, and a removable element operatively connecting said device to said arm, said guide member and adjustment device being provided with indicia for indicating their adjusted settings.

18. In combination with a stoker assembly including a retort, a source of air supply and a conduit for conducting air from said source to the retort, a frame, a draft regulating member carried by the frame and arranged for control movement in said conduit in response to the flow of air through the conduit, an inertia member tending to oppose control movement of said regulating member, pivotally carried by the frame, an arm also carried by the frame and movable responsively to control movement of said regulating member, and means associated with said arm and forming therewith an operative connection between said members, said means comprising a guide member pivoted to the frame, a lever connecting the guide member to said inertia member, an adjustment device slidably carried by said guide member and provided with grooves in a face portion thereof, and a removable element carried by said arm and adapted to seat in any one of said grooves, for operatively connecting the arm in adjusted relation to said device.

BERNARD MORSE GUTHRIE.
